CLAIM

The ornamental design for a machine for grating, slicing and/or grinding foodstuffs, as shown.

DESCRIPTION

FIG. 1 is a front perspective view of the top and one side of a machine for grating, slicing and/or grinding foodstuffs showing my new design;

FIG. 2 is an elevational view of the side opposite that shown in FIG. 1;

FIG. 3 is a rear elevational view thereof; and

FIG. 4 is a top plan view thereof.
